UNITED STATES PATENT OFFICE.

RAYMOND D. SMITH, OF MILTON, MASSACHUSETTS, ASSIGNOR TO TREMONT PRODUCTS COMPANY, OF BOSTON, MASSACHUSETTS, A CORPORATION OF MASSACHUSETTS.

THERMOSTATIC LAMP DIMMING PULL SOCKET.

Application filed November 3, 1920. Serial No. 421,554.

To all whom it may concern:

Be it known that I, RAYMOND D. SMITH, a citizen of the United States, residing at Milton, in the county of Norfolk and Commonwealth of Massachusetts, have invented a new and useful Thermostatic Lamp-Dimming Pull Socket, of which the following is a specification.

This invention relates to improved sockets and particularly pull sockets, incorporating in novel and advantageous combination a plurality of different and convenient light-controlling functions that in preferred form are selectively available by the user, 10 through actuation of the usual pull chain.

In general the object of the present invention is to provide a lamp-socket, (and specifically though not exclusively, a pull-socket) having a greatly increased field of 20 usefulness in its control of both the degree and periodicity of illumination produced by the usual incandescent lamp through the above mentioned novelly combined features of switch function,—such features in the 25 present instance comprising preferably the ability, through consecutive full or partial strokes on the single switch-operating pull chain, selectively and respectively to switch into and out of circuit the usual incandescent lamp of desired candle power for full 30 illumination and to switch into and out of series with this lamp a resistance unit compactly arranged as part of the socket switch structure and for continuous duty when desired, this unit operating to dim the lamp when switched into circuit therewith; and also the ability, when through with the 35 light to operate the switch to cause thermostatically delayed, automatic extinguishment of the lamp an appreciable interval of time after actuation of the pull chain, so that full illumination may be had for leaving the premises.

A specific object of the present invention 40 is so to construct and locate the lamp-dimming resistance unit within the socket switch structure that an outer telescopically enclosing casing may be employed as usual and properly formed to support the interior 45 socket-switch structure in the usual manner, i. e., by shoulder engagement with the bottom insulating switch base, such casing being further suitably formed to permit of ready dissipation to the atmosphere of heat 50 generated in said unit, so that such heat

may not accumulate in the socket-switch structure to the impairment thereof, or of the lamp base.

A further object is to provide a simple arrangement of switch-controlling mechanism 60 which shall render the switch selectively operable manually to a maximum degree, and specifically but not necessarily, so that consecutive full pulls upon the switch-operating chain shall operate alternately to light 65 and extinguish the lamp in the usual manner, but so that either of the heretofore described special light-controlling switch functions are available at will through less than a full actuating stroke upon the pull 70 chain.

Other objects reside in the retention, in my improved pull-socket, of substantially all the important and advantageous features of modern conventional socket-switch 75 design and construction, so that any new parts employed for producing the new functions are readily adaptable for efficient production through the usual processes of socket manufacture. Such features include 80 the method of securing the stationary inclined contact plates to the insulating socket base; the structural arrangement of the socket structure as a whole, and the manner of incorporating therein the lamp-dimming resistance unit so that maximum efficiency and simplicity of assemblage together with ready accessibility for adjustment of the main switch-operating spring 85 is had; and also include the structural means by which proper circuit connections through the switch are securely made through the clamping of the several interior lead terminals to the insulating socket base, such construction avoiding all requirement 90 for soldered connections and ensuring uniformity and permanency in the finished product.

For purposes of illustration only, the present improvement is disclosed as embodied in an "adapted" type of pull socket as appears in the accompanying drawings in which:—

Fig. 1 is a plan view of my improved pull-socket with casing and upper insulating cap omitted and certain parts shown in section for clearness, the position of the switch being that in which the main lamp alone is operatively supplied with current.

Fig. 2 is a view in front elevation, show-

ing the complete pull-socket switch, with the casing and certain other parts broken away to show the interior parts.

Fig. 3 is a diagram of electrical connections. The mechanical parts represented therein appearing in merely arbitrary positional relation.

Fig. 4 is an enlarged view of the current switching parts, looking in direction of arrow 4, Fig. 1, and showing the rotor advanced to engage the detent hook.

Fig. 5 is a partial view in elevation looking at the right of Fig. 2, with casing broken away.

15 In the drawings, a single part when appearing in more than one view is designated by the same reference numeral.

20 My improved socket-switch is composed, as usual, of an insulated cap 10 and an insulated base 11 held by screws to the electrically insulated bell-mouth bracket 13, and to the supply lead brackets 14, and 15, the former of which is in electrical contact with the threaded receptacle 17 for the main lamp 25 67 through the holding screw 18 (Fig. 1).

25 The central vertical pivot stud 20 is adjustably seated in recesses formed respectively and centrally in the insulating cap and base, and pivotally carries the usual oscillatory segmentary actuator 21, the coiled spring 22 for rotatively returning the latter after its stroke, and the double-ended conductive rotor 23, all of these parts being axially slideable upon the insulated pivot stud 20 and pressed axially downwardly thereon against inclined detent steps formed on the insulating base 11, by the axial tension in said spring 22 as in the common form of pull-socket switches well known in 30 the art. The present improvement contemplates the accomplishment of the cited objects principally through the rearrangement of stationary contact plates carried on the inclined faces of said detent steps, over 35 which the rotor 23 rides under tension of spring 22 to make and to break the circuits.

40 A ready understanding of the nature of this rearrangement of contact plates may best be had through comparison thereof with the usual and well known arrangement of corresponding contact plates in the simple conventional type of make-and-break pull-socket switch. In the latter type of switch it is well known to those skilled in the art 45 that the circuit is controlled through the conductive rotation of the rotor wiper arms 25 over diametrically opposite and similarly inclined contact carrying detent steps, such steps being generally of 90° circular extent and four in number, and a pair of opposite steps carrying contact plates connected as suitable circuit terminals for connecting the lamp to the supply circuit when conductively bridged by the rotor arms. Also in 55 the familiar switch construction just de-

scribed, it is well known that each of said detent steps terminates in an abrupt insulating shoulder formed on the insulating base, to prevent retrogressive movement of the rotor arms 25 between steps.

70 In Figs. 1 and 3 of the drawings, four such insulating step shoulders 30 appear in equally spaced relation these shoulders being understood to occupy a position relative to the heretofore described switch parts substantially the same as in the simple conventional make-and-break type of pull-socket switch before mentioned. This construction gives rise to the usual operation, i. e., that

75 the actuator (which is normally positioned against stop 31 depending from bracket 15 and is free for limited swinging movement between said stop and the dummy stop bracket 32) possesses an oscillatory travel of slightly more than 90°, the latter being substantially the circular spacing of step shoulders 30, so that the actuator at each full stroke thereof, drives the rotor 23 by ratchet engagement therewith, so that each of the arms 25 is advanced completely over one de-

80 tent step and its terminating step shoulder 30 with a quick snap action and onto the succeeding step, such action taking place simultaneously with both rotor arms. But

85 in the present improvement, two of the detent steps, (specifically those steps which, in the simple make and break type of pull-socket switch, are blank) are divided in halves, and two additional intermediate insulating shoulders 33, 33, are formed, thus

90 producing two inclined detent steps in place of each of the said original blank steps.

95 Thus there are in my improved socket one pair of contact carrying steps 36, 36 of 90° extent, circularly separated by two pairs of 105 45° steps, one of which latter pairs, comprising steps 34, 34, is blank and the other pair 35, 35, carry additional contact plates.

110 The electrical connections of these step-carried and inclined contact plates is evident from Fig. 3, it being noted that a single supply circuit contact 40 occupies both steps 35 and 36 on one side of the switch; that a single contact plate 41 occupies the opposite short step 35, and that two separate contacts 42 and 43 occupy the base and top respectively of the other detent step 36.

115 Contacts 40 and 43 each terminate diametrically opposite each other and at their uppermost portion, in the angular formation shown in Fig. 4, where the end of the wiper arm is shown as having rotatively passed the apex or summit of this angular formation, and is positioned on the sloping terminal of contact 43 to be discharged therefrom by the axial tension in spring 22. The detent hook 44, however, is pivoted on the base mounted stud 45 and is normally positioned to intercept one of the two spurs 46 on the wiper arms when the end of either of these

arms has reached the rotative position shown in Fig. 4, thereby to prevent further rotative travel of the arm relative to the contact plate 43—which further travel is necessary 5 for permitting its tension caused discharge from the sloping contact terminal as described above. The said detent hook is held in its intercepting position by insulated pin-and-slot engagement therewith of the free 10 end of a flexing, bi-metallic thermostat 50, mounted at its opposite end on the bracket 13, so long as the former is normally cool, and until the thermostat 50 (which carries an insulated heating resistance winding 51 15 electrically connected to be energized only in the position of the rotor as shown in Fig. 4) is heated by the current and flexes outwardly to retract the hook 44 from the path of spur 46 and permits the wiper arms 25, 25 20 to be discharged simultaneously as described from contacts 43 and 40 to break the circuit through the main lamp.

In the preferred form of my invention, I utilize as a resistance unit for dimming 25 the lamp, a fine resistance wire 52 wound on a separate metallic shell 53 and insulated therefrom by a layer 54 of mica, asbestos paper, refractory cement, or other suitable material as desired. A similar insulating 30 layer 55 may be applied to cover the resistance wire 52 and protect the winding. Or, if desired, I may mould a solid body of cement. The shell 53 on which the resistance wire is wound surrounds the usual lamp receptacle, being sufficiently greater in diameter, however, to provide a generous air 35 space between the shell and receptacle to aid in the dissipation of heat. The receptacle 17 and shell 53 are both secured to the 40 bottom surface of the lower insulating block 11 by means of flanges such as shown at 56 in Fig. 2, this particular flange being held by and insulated from the screw 57 engaging bracket 15.

45 The electrical connections through the switch as indicated diagrammatically in Fig. 3 are produced in the structure as follows.

One end of the lamp-dimming resistance wire 52 has a terminal foil lead 58 extending 50 to, and clamped beneath, the head of screw 60 which screw also holds the contact plate 41 on detent step 35. The other end of 55 resistance wire 52 has a similar terminal foil lead 59 clamped beneath the bell-mouth bracket 13 in contact with an extension as usual for electrical connection with the lamp terminal contact tongue 64. Also clamped in electrical contact with the extension 66 of contact 42 is one end 71 of a connection 60 lead from the thermostat resistance winding 51, the other end of which winding has a connection lead 70 extending to beneath the head of a screw 72, that in a manner similar 65 to screw 60 firmly holds contact 43 to the insulating base 11 and properly positioned

on detent step 36. Suitable insulation 73 insulates the bell-mouth bracket 13 from all metallic lead conductors that are clamped between it and the base 11. The long contact plate 40 occupying detent steps 35 and 70 36, is extended to be clamped beneath and in electrical contact with the supply lead bracket 13 in the usual and well known manner as clearly shown in Fig. 5.

My improved switch operates as follows: 75

In Fig. 1 the rotor 23 is shown in a position bridging and electrically connecting contacts 40 and 42. Current is thus supplied directly to only the lamp which is thus adapted for continuous operations at full 80 brilliancy.

When desired to extinguish the lamp, a full stroke upon the pull chain 75 will cause the actuator 21 to advance the rotor 23 into its position as shown in Fig. 4, where resistance is offered to the further travel of said rotor by engagement of hook 44 with spur 46, formed on the rotor arm 25, such resistance being readily felt by the hand of the operator. If it be desired to cause delayed extinguishment, the chain is then released and the wiper remains in its arrested position until released by the thermostatic action as heretofore described. If it is desired to effect immediate extinguishment 95 without delayed action, the stroke on the pull chain is completed against the resistance of hook 44, which as shown in Fig. 1 is bevelled in a manner to produce a retracting tendency of the detent hook when the latter is subjected to a sufficiently strong thrust by the spur 46. The light is now extinguished and the wiper arms occupy a position as indicated in broken lines in Figs. 3 and 4.

100 The operative effect of the next single actuation the pull chain 75 is also optional. A half stroke on the chain suffices to rotate the wiper to a position for bridging contacts 40 and 41, in which position the lamp-dimming 105 resistance 52 and lamp 67 are connected in electrical series to the supply circuit which causes the main lamp to burn dimly;—or a full stroke on the chain advances the wiper to its operative position shown in Fig. 1, where the main lamp alone is energized and 110 burns at full brilliancy.

115 It is thus evident that consecutively full strokes upon the chain will operate merely to light and extinguish the main lamp in the usual manner, but that if suitable partial strokes be given to the pull chain the operative effects of delaying the extinguishment of the lamp and of dimming the lamp may be secured selectively at their respective 120 places in the cycle of operative movements.

125 It will be understood, however, that no restrictions are intended to be imposed upon my invention through illustration of this particular sequence of operation. The sequence with which these operations may be 130

had is merely a matter of choice in predetermined arrangement; also, it will be apparent to those skilled in the art, that in adapting my herein disclosed invention to commercial use, the precise arrangement disclosed may readily be varied so that delayed automatic actuation of the switch may be had to produce switch movement from any stage to any other stage,—and not only from fully lighted to extinguishment, as I have specifically shown the chosen construction to be arranged. Any such modification is a mere matter of choice in arrangement.

A curved chain guard 77 is shown extending from and secured to the bracket 14 and may be formed of fibre or other suitable material for insulating the live parts from accidental contact by the pull chain 75, or other moving parts, that must be insulated.

Conventional provision for mounting my improved switch in an ordinary socket appears in the upper threaded plug 78 and centre contact 79 which are electrically connected respectively with brackets 14 and 15 by screw 80 and by the screw 81, relay plate 82, and screw 83 respectively, it being noted, however, that in its entirety the advantageous switch arrangement which I have invented and herein described is as readily capable of embodiment in a fixture or permanent type of socket, or a pendant pull switch, etc., as in the adapter type of lamp socket herein shown. The casing 76, may be extended in bell form to serve as shade holder or as shown in Fig. 2.

The feature residing in the thermostatic control mechanism 50, 45, 44, 43, 42, etc. per se is not claimed in this application, but is the subject matter of claims in my two co-pending applications, Serial No. 421,556, filed November 3, 1920 and Serial No. 421,555, filed November 3, 1920. Neither is the feature residing in the arrangement of contact steps 30, 33, 34, etc. relative to the rotor 23 and in combination with the resistance unit, 51, 52, 53, 54, etc. claimed in this application, but is the subject matter of claims in applicant's issued Patent No. 1,343,689. Also the feature residing in the construction and mounting of the resistance unit 51, 52, 53, 54, etc., per se, is not claimed in this application, but is the subject matter of claims in applicant's issued Patent No. 1,343,690.

The above, and many other modifications of the exact embodiment of my invention as herein disclosed, may be readily made;—and without intention, therefore, of limiting the scope of the invention to such exact embodiment, what I claim as new is:

1. A pull socket switch structure embodying, in combination, a lamp receptacle; means to dim the lamp; a controlling switch; and a device operatively related to said switch, electrically governed thereby,

and adapted when electrically energized to cause delayed circuit-breaking switch movement to extinguish the lamp; together with manual actuating means for establishing selective operative positions of said switch whereby the lamp may respectively be fully lighted, dimmed, or automatically extinguished a substantial period of time after manual actuation of said switch to energize said device. 70 75

2. A socket switch having three elements to be energized, and comprising in combination; a plug receptacle to receive an electrical device; a resistance; and means operative, when electrically energized, to cause automatic controlling movement of a contained switch; and contained switch mechanism including differently positioned stationary contacts for a circuit to energize said plug receptacle and resistance in series, and for a circuit to energize said means simultaneously with one of said last mentioned two circuits; together with a single, manually-actuable movable governing element whereby either of said three circuits may selectively be connected to the supply circuit. 80 85 90

3. A self-contained socket switch structure including a current-governing switch and three translative devices to be governed thereby, comprising respectively a current tap receptacle, a resistance and electrically-operable automatic means for causing delayed circuit governing actuation of said switch;—the said switch having a movable current distributor and co-operative stationary contacts connected as terminals respectively for a circuit containing said receptacle alone, and for a circuit containing said receptacle and said means, whereby through movements of said distributor said circuits may selectively be supplied with current. 95 100 105

4. A self-contained socket switch structure adapted for connection to a supply circuit and having three electrical translative devices to be supplied with current from said circuit comprising a load tap receptacle; a resistance; and electrically-controlled means operative when energized to cause the automatic disconnection of said receptacle from the supply circuit; together with a contained switch mechanism for governing the supply of current to said devices and embodying a movable, conductive distributor adapted to be manually actuated, and separate stationary contacts arranged to be conductively engaged respectively by said distributor in different positions of the latter and electrically connected when so engaged to energize either said receptacle alone, said receptacle and said resistance in series, or said receptacle together with same means. 110 115 120 125

5. A pull socket switch structure includ-

- ing a current governing switch and three translatable devices to be governed thereby, comprising respectively a current tap receptacle; a resistance; and electrically-operable 5 means for causing automatic circuit-governing actuation of a contained switch;—the said switch including a rotatable current distributor, a spring returned oscillator driving element having pawl-and-ratchet engagement with said distributor for rotatively advancing the latter in progressive states of movement, detent means arranged to restrict retrogressive movement of said distributor, and stationary contacts arranged in the path 10 of said distributor and connected as terminals respectively for a circuit containing said receptacle alone, for a circuit containing said receptacle and said resistance in series, and for a circuit containing said receptacle and said electrically operable 15 means; together with a pull chain for manually actuating said driving element, whereby said distributor may be selectively established in different positions for selectively 20 energizing said circuits respectively.
6. A pull socket switch structure including a current-governing switch and three electrical load devices to be governed thereby, comprising respectively a current tap receptacle; a resistance; and electrically-operable 25 means for causing automatic circuit-governing actuation of said switch,—the said switch including a rotatable current distributor, a spring-returned oscillatory driving element having pawl-and-ratchet engagement with said distributor whereby successive full strokes of said element advance said distributor in full stages of rotative movement, detent means to restrict retrogressive movements of said distributor, and separate stationary contacts arranged in the path of said distributor,—and electrically connected as terminals respectively for a circuit containing said receptacle, a circuit containing said receptacle and said resistance in series, and for a circuit containing said receptacle and said means;—said stationary contacts for a plurality of said circuits being consecutively spaced within a full stage of movement of said distributor, whereby a single stroke of said element is operative selectively to control a plurality of said circuits.
7. A self-contained socket switch structure including a current-governing switch and three translatable devices to be governed thereby, comprising, respectively a current tap receptacle, a resistance, and electrically-operable means for causing automatic circuit-governing actuation of the switch;—the said switch having a double-ended, centrally-pivoted, conductive rotor; a stationary supply-connected contact circularly extended in the path of the rotor ends, separate stationary contacts circularly disposed in the path 65 of the rotor ends but on the opposite side of the rotor pivot from said supply-connected contact, the said separate contacts being connected as terminals respectively for a circuit containing said receptacle alone, for a circuit containing said receptacle and said means, whereby the supply of current to said circuits may be selectively established through the conductive bridging by said rotor of said supply-connected contact and selected members of said separate contacts.
8. A pull socket switch structure adapted for supply circuit connection and including a lamp receptacle; a lamp dimming resistance; electrically-operable means adapted automatically to cut out said receptacle from the supply circuit; and contained switch mechanism embodying a rotatable current switching member having two diametrically opposite contact wiping arms; a rotatively oscillatory spring-returned, pull-operated driving segment having stop means to limit the rotative stroke thereof, and having pawl and ratchet engagement with said member, whereby successive full strokes of said segment cause full rotative advance movements of said member; circularly positioned inclined detent steps arranged about said end of said pivot in the rotative path of said wiper arms and terminating respectively in insulating shoulders for preventing retrogressive movement of said arms between steps; separate contact plates carried on the incline portions of said detent steps to cooperate with said current-switching member and electrically connected as terminals respectively for one side of the supply circuit, for a load circuit containing said receptacle alone, for a load circuit containing said receptacle and said resistance in series, and for a load circuit containing said receptacle and said electrically-operable means, said contact plates being so consecutively spaced that more than one of said load-circuit contact plates is traversed by a wiper arm during a full advance movement of said member, whereby partial and full strokes of said segment establish connection of respectively different load circuits to the supply circuit.
9. In a thermostatically-controlled, lamp-dimming socket switch structure, embodying a movable switch contact member and means tensioning the same for current switching movement when manually energized through manually-caused movement of said member, in combination: lead terminals adapted for the connection of said structure to the supply circuit; a structure-mounted lamp receptacle; a structure-mounted resistance for dimming the lamp; a detent device normally arranged to prevent said tension-caused current-switching movement of said member, and adapted when electro-thermally energized to permit said movement after a substantial period of delay; separate stationary contacts positioned to be conductive 125 130

- tively traversed by said member for switching the current; and circuit connections between said lead terminals, said receptacle, said resistance, said device, and said contacts, 5 so arranged that in different positions, said member is operative to establish the energization of said receptacle, said resistance and said device respectively in selective and different electrical relations.
10. A current-supplied socket switch structure embodying in combination; a receptacle for an incandescent lamp; a structure-contained resistance unit for dimming said lamp; a lamp-governing switch with an electrically energizable device normally operative to delay lamp-extinguishing, circuit-breaking action of said switch; and common manual switch-operating means for tensioning said switch automatically to effect said circuit-breaking action, and for operatively energizing said device;—the said switch including a manually-actuable current-switching member, and co-operative separate contacts arranged to be electrically connected in variable relation to the supply circuit in different positions of said member, together with circuit connections between said contacts and said receptacle, unit, and device respectively so arranged that in one position of said member said lamp alone is energized, in another position of said member said lamp and said unit are energized in series, and in a different position of said member, 20 said lamp and said device are together energized, whereby automatic delayed extinguishment of said lamp is effected.
11. A socket switch having a lamp; a resistance for dimming said lamp; and automatic, electrically-governable means to cause the delayed cut-off of current to said lamp;—together with a switch embodying separate contacts governing three circuits respectively containing said lamp, resistance and means, and a co-operative manually 25 movable circuit controller arranged by a first movement thereof to energize said lamp in series with said resistance, by a second movement thereof to energize said lamp alone, and by a third movement thereof to energize said means together with said lamp, thereby to cause the said delayed cut-off of current to said lamp.
12. In a pull socket for an incandescent lamp; means to dim the lamp; a current-supplied switch including a current-distributing rotor and co-operative contacts arranged to govern the energization of said lamp and said means; a device electrically governed by said switch, operatively related thereto 30 mechanically, and adapted when energized to cause delayed automatic lamp-extinguishing actuation of said switch; and circuit connections to said switch contacts, and to said receptacle, said means, and said device, respectively, whereby said latter three parts
- are energizable in variable combinations by said switch; together with a manually-actuable spring-returned, reciprocal driving element arranged to rotate said rotor through a single and a double stage of movement respectively by partial and full strokes thereof, the arrangement of said co-operating contacts being such that successive full strokes of said element position said rotor alternately to light and extinguish the lamp, 70 and further so that partial strokes of said element operate respectively to dim the lamp and to cause delayed automatic extinguishment thereof.
13. An incandescent lamp socket structure 80 adapted for connection to a supply circuit and incorporating, in self-contained form, a lamp receptacle; two separate resistance units; and a switch arranged to govern the connection to the supply circuit respectively 85 of said receptacle alone, and of said receptacle in series with either of said two resistance units,—one of said units being arranged solely to dim the lamp; together with means including the other of said units 90 operative when energized to cause automatic current switching actuation of said switch.
14. A pull socket switch structure embodying, in combination; a lamp receptacle; means to dim the lamp; a controlling switch; a device operatively related to said switch, electrically governed thereby, and adapted when electrically energized to cause delayed automatic switch movement to vary the supply of current to the lamp; together with 100 manual actuating means for establishing selective operative positions of said switch, whereby the lamp may respectively be lighted, dimmed or extinguished; said device being arranged to be rendered operative by movement of said manual actuating means subsequent to a movement thereof that establishes the switch in one of its said operative positions.
15. In a pull-chain, lamp-socket switch 110 adapted to be operated by successive actuations of a controlling pull chain and incorporating agencies operative to dim the lamp and also to delay lamp extinguishment, means whereby said pull chain may be actuated at will to light the lamp, to dim the same or to set in operation said delayed action extinguishment agencies.
16. In a pull-chain, lamp-socket switch 115 adapted to be operated by successive actuations of a controlling pull chain, and incorporating agencies to dim the lamp and also to delay circuit breaking movement of the switch, means whereby said pull chain may be actuated at will to light the lamp, to dim the same, or to establish the switch under the control of said delayed action agencies, or to move the switch directly to break the circuit without delay.
17. In a pull-chain, lamp socket switch, 120

- the combination with pull chain control means of automatic mechanism to cause self delayed lamp extinguishment, circuits operative respectively to produce relatively 5 high or low candlepower illumination and means whereby said control means may be actuated to establish at will said circuits for either relatively high or low illumination or to cause self delayed lamp extinguishment.
- 10 18. In a pull-chain, lamp socket switch, the combination with pull chain control means of automatic mechanism to cause self delayed lamp extinguishment, circuits operative respectively to produce relatively 15 high or low candle-power illumination and means whereby said control means may be actuated to establish at will said circuits for either relatively high or low illumination or to cause self delayed lamp extinguish- 20 ment, or to move the switch directly for lamp extinguishment without delay.
19. In an electric light switch, the combination with circuits operative to produce either relatively high or low candle-power
- illumination, of controlling means to es- 25 tablish or break said circuits at will and means also set into operation by said controlling means automatically to delay lamp extinguishment for a substantial interval.
20. In an electric light switch, the combi- 30 nation with circuits operative to produce either relatively high or low candle-power illumination, of controlling means to es- 35 tablish or break said circuits at will and means also set into operation by said con- trolling means automatically to delay lamp extinguishment for a substantial interval, said controlling means being also operable at will to cause lamp extinguishment directly without said interval of delay. 40

Signed at Boston, in the county of Suffolk and Commonwealth of Massachusetts, this 25th day of October, 1920.
